CLAIM

The ornamental design for a cable controller for an electrocardiogram electrode placement system, as shown and described.

DESCRIPTION

FIG. 1 is a top perspective view of a cable controller for an electrocardiogram electrode placement system, showing our new design;

FIG. 2 is an exploded view thereof;

FIG. 3 is a top plan view thereof;

FIG. 4 is a bottom plan view thereof;

FIG. 5 is a side elevation view thereof;

FIG. 6 is a side elevation view thereof;

FIG. 7 is a front elevation view thereof;

FIG. 8 is a rear elevation view thereof; and,

FIG. 9 is a top plan view of the cable controller used with an electrocardiogram electrode placement system.

The broken lines in FIG. 7 illustrate portions of the cable controller that form no part of the claimed design, and the broken lines in FIG. 9 represent environmental subject matter only and form no part of the claimed design.

1 Claim, 7 Drawing Sheets
